(57) **CLAIM**

The ornamental design for a dog harness, as shown and described.

DESCRIPTION

FIG. 1 is a top plan view of a dog harness showing my new design;

FIG. 2 is a bottom plan view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top, front, right perspective view thereof;

FIG. 8 is a rear perspective view of the dog harness, shown in an environment of use;

FIG. 9 is a front perspective view of the dog harness, shown in an environment of use; and,

FIG. 10 is a side perspective view of the dog harness, shown in an environment of use.

The broken lines shown in the figures depict portions of the dog harness that form no part of the claimed design. The broken lines showing a portion of gated area and dogs in FIGS. 8, 9, and 10 are for environmental purposes only and form not part of the claimed design.
